(57) CLAIM

The ornamental design for a massage chair, as shown and described.

DESCRIPTION

FIG. 1 is a front elevational, environmental view of a massage chair showing a new design;

FIG. 2 is a rear elevational, environmental view thereof;

FIG. 3 is a right side elevational, environmental view thereof;

FIG. 4 is a left side elevational, environmental view thereof;

FIG. 5 is a front, right side perspective, environmental view thereof; and,

FIG. 6 is a front, left side perspective, environmental view thereof.

The broken lines shown in the drawing views are included for illustrative purposes only, and form no part of the claimed design.
